TWENTY-KEY SECRETARIAL ANSWERING CABINET

George M. Janda, Westchester, and John Wainovich, Jr.,
Schaumburg, Ill., assignors to GTE Automatic Electric
Laboratories Incorporated, North Lake, Ill.

Filed Jan. 27, 1975, Ser. No. 544,435

Term of patent 14 years

Int. Cl. D14—03

U.S. Cl. D26—14 A

FIG. 1

FIG. 2

FIG. 3

FIG. 4

FIG. 5

FIG. 1 is a perspective view of a twenty-key secretarial answering cabinet, showing our new design;

FIG. 2 is a top plan view, to a reduced scale;

FIG. 3 is a front view, to a reduced scale;

FIG. 4 is a rear view, to a reduced scale; and

FIG. 5 is a side view (the opposite side being a mirror image thereof), at a reduced scale.

We claim:

The ornamental design for a twenty-key secretarial answering cabinet, as shown and described.
